ROLL HOLDER

Samuel N. Hope, Wauwatosa, Wis., assignor to
 Griffith-Hope Company, West Allis, Wis., a
 corporation of Wisconsin

Application June 24, 1938, Serial No. 215,592

5 Claims. (Cl. 242—55.2)

This invention relates to holders for sheet material in roll form, such as paper toweling.

An object of the invention is to provide an inexpensive and efficient holder for dispensing paper or other sheet material from a roll, the holder having simple but effective means for braking the roll when the end portion of the material is to be severed.

Another object of the invention is to provide improved but simplified supporting means for rotatably carrying the roll.

The invention further consists in the several features hereinafter described and claimed.

In the accompanying drawing, illustrating one specific embodiment of the invention:

Fig. 1 is an end elevation of a roll paper holder constructed in accordance with the invention;

Fig. 2 is a front elevation of the holder, parts being broken away and parts being shown in section, and

Fig. 3 is a view similar to Fig. 1 but showing the roll as it appears when braked by tensioning the paper end.

In the drawing, 10 designates a sheet metal wall plate or back plate which is adapted to be secured to a supporting wall 11 by screws 12 passing through key-hole slots 13 formed in the plate. The upper portion of the plate is bent forwardly and has a horizontally extending curled edge or bead 14, and the lower portion of the plate is bent to form a forwardly projecting V-shaped shoulder-forming rib or bead 15 extending parallel to the curled edge 14, the rib being spaced approximately vertically below the curled edge and projecting a short distance from the plane of the wall plate.

A bail-shaped hanger 16 formed of round wire has a shaft-like intermediate portion 17 pivotally confined in the bearing formed by the curled edge or bead 14 of the wall plate, and has resilient depending arms 18 at opposite ends provided with curved or arched inturned projections 19 to loosely enter a roll 20 of sheet material, such as paper toweling, preferably having lines of weakening 20' at intervals. The inturned projections or ends 19 extend longitudinally of the roll and approximately in the plane of the arms 18. In many instances, the roll 20 has a tubular core 21 on which the sheet material is wound. The roll is eccentrically and rotatably supported on the arched projections 19 which engage the upper portion of the inner cylindrical surface of the core at points spaced from the ends of the core so that if the core ends should be damaged they will not interfere with the rotation of the roll. The hanger 16

is suspended in inclined position from the wall plate, the projections 19 being forward of the pivotal axis of the hanger. The free end 22 of the paper hangs from the front of the roll. The roll bears at its rear portion against the narrow front edge portion of the rib 15 of the wall plate, the rib extending parallel to the roll. The distance between the pivotal axis of the hanger 16 and the roll-supporting projections 19 is approximately the same as the distance between this axis 10 and the rib 15. When the hanger is in its normal suspended roll-supporting position the braking rib 15 extends behind the lower end portion of the hanger.

The roll 20 is applied to the holder by entering 15 one end onto one of the hanger projections 19 and then springing the other projection so as to permit it to enter the other end of the roll.

When paper is to be dispensed from the roll, the free end 22 of the paper is drawn outwardly by 20 hand in an approximately horizontal direction from the top of the roll, as indicated by dotted lines in Fig. 1. During this withdrawal the roll will turn without excessive resistance. When the desired length of paper is unwound from the roll, 25 the paper end 22 is swung downwardly to extend from the front of the roll in an approximately vertical position, as indicated by full lines in Fig. 1, and downward tension is applied to the paper end, whereupon the roll will be pressed against 30 the rib or bead 15 and be prevented from rotating. This pressure will usually cause indentation of the roll, as indicated in Fig. 3. The eccentric mounting of the roll on the hanger projections 19 aids the rearward urging of the roll against the 35 braking rib 15, since the downward tension of the paper end at the front of the roll tends to swing the roll rearwardly on these projections. Sufficient tension on the paper will then cause the paper to tear off along a line of weakening 20'. As 40 the roll becomes smaller, the roll-supporting hanger 16 swings rearwardly to a steeper angle, but the relation of the rib 15 to the roll remains such as to secure the desired braking or locking action.

The holder will accommodate rolls of widely different diameters and rolls having core openings of widely different diameters. In addition, rolls which vary somewhat in length can be used on the holder.

The claimed subject-matter of the present application includes features which are also disclosed in my copending application for Roll paper holders, Serial No. 215,591, but the claimed subject-matter of the latter application embraces 55

additional features which are not disclosed in the present application.

What I claim as new and desire to secure by Letters Patent is:

- 5 1. A roll paper holder, comprising a wall plate having a brake projection with a narrow roll-indenting edge, and a hanger pivotally mounted on said plate at a higher elevation than said projection, said roll-indenting projection being approximately vertically below the pivotal axis of said hanger and extending parallel thereto and behind the lower end portion of said hanger, and said hanger being adapted to rotatably support a roll of paper thereon with said roll bearing at its 10 rear against said projection and with the free end of the paper at the front of the roll, the paper end when tensioned downwardly causing said roll to press rearwardly against said projection for braking said roll, whereby to facilitate severance of the paper.
- 15 2. A roll paper holder, comprising a sheet metal wall plate having a portion bent therefrom to form a forwardly projecting roll-indenting rib rigid with said plate, and a hanger pivotally mounted on said wall plate at a higher elevation than the rib, said rib extending substantially parallel to the pivotal axis of said hanger and extending behind the lower end portion of said hanger, and said hanger being adapted to rotatably support a roll of paper thereon with said roll bearing at its rear against said rib and with the free end of the paper at the front of the roll, the paper end when tensioned downwardly causing said roll to press rearwardly against said rib for braking said roll, whereby to facilitate severance of the paper.

3. A roll paper holder, comprising a support, a hanger pivotally mounted on said support to rotatably carry a roll of paper thereon eccentrically of the roll and above the axis of the roll, said support having a braking projection presenting a roll-indenting edge against which the rear portion of the roll is adapted to bear, said braking projection being rigid with said support and extending behind the lower end portion of said hanger, and said roll being urged rearwardly against said projection by downward tension on the free end of the paper, whereby to facilitate severance of the paper.

4. A holder for a paper roll with open ends, comprising a hanger with wire arms each having an inwardly and upwardly bent arched free end adapted to enter an end opening of the roll and forming a rounded bearing surface engageable with the inner surface of the roll at a distance from the end of the roll, said arched ends extending substantially in the plane of said arms.

5. In a roll paper holder, the combination of supporting means, and a hanger pivotally mounted on said supporting means for rotatably carrying a roll of paper thereon eccentrically of the roll and above the axis of the roll, said supporting means having a braking projection with an edge adapted to be engaged by the rear portion of the roll, the distance of said projection from the pivotal axis of said hanger being substantially the same as the radius of said hanger, said roll being urged against said braking projection by tensioning the free end of the paper, whereby to facilitate severance of the paper.
